LEE E. HOWARD AND MARGUERITE E. HOWARD, OF LOS ANGELES, CALIFORNIA.

NONBREAKABLE DRESSED DOLL.

Application filed June 17, 1927. Serial No. 199,497.

Our invention relates to toys and more particularly to a non-breakable doll and a method of making the same.

The primary object of our invention is to provide a neatly dressed non-breakable doll of the so-called "rag doll" type.

A further object is to provide a novel method of producing a doll of the character described in a simple and inexpensive manner.

Other objects and advantages will appear hereinafter, and while we show herewith and will describe a preferred form of construction, we do not desire to limit ourselves to such preferred form but that various changes and adaptations may be made therein without departing from the spirit of our invention as hereinafter claimed.

Referring to the drawings which accompany this specification and form a part thereof,

Fig. 1 is a front view of a doll made by the method embodied in our invention.

Fig. 2 is a left side view of the doll shown in Fig. 1.

Fig. 3 is a plan view of a sock from which the body part of the doll shown in Figs. 1 and 2 is made, with cutting lines indicated thereon by dotted lines.

Fig. 4 is a view, in front elevation, of that portion of the sock which is used for making the head, trunk and legs of the doll, as it appears before being stuffed.

Fig. 5 is a similar view of the sock part shown in Fig. 4 after it has been turned, stuffed and sewed up ready for dressing.

Fig. 6 is a side view of the second sock used in making the doll, in position to be pulled over the stuffed body shown in Fig. 5.

Fig. 7 is a plan view of one of the cut-off parts of the first sock which is used to form one of the doll's arms, as sewed preparatory to being stuffed.

Fig. 8 is a similar view of the arm part shown in Fig. 7 after it has been turned and stuffed.

The doll, as shown, is made for the most part, of a pair of common knit socks, preferably men's socks of the mottled variety, red and white, blue and white, brown and white, etc., with white heel, toe and ribbed top. One of the socks is flattened out as shown in Fig. 3 and cut across the foot part 10 thereof on line 11. The cut-off part is then cut longitudinally on line 12 to form two equal folded pieces 13, small pieces of which are cut away

on lines 14, at the toe end, to give them a more nearly uniform taper. The heel and leg portions 15 and 16 respectively, of the sock are left in one piece, the body piece and the ribbed top part 17 of the leg portion is slit along its opposite folded edges, as at 18, throughout nearly its entire length.

The body piece is now turned wrong side out and the leg part thereof is folded in a plane at right angles to the original fold so as to form two similar appendages 19 which serve as the doll's legs. The coinciding edges of each folded leg 19 are then sewed together, producing a continuous inner seam 20 and seams 21 are run across the lower ends thereof. The body casing thus formed is now turned right side out and cotton or other suitable material is stuffed into opening 22, left by the original cut on line 11, until the leg, body and head parts thereof are well rounded out to the form shown in Fig. 5. Opening 22 is finally drawn together and sewed up as at 23.

Pieces 13 are now turned wrong side out and the cut edges of each are sewed together forming seams 24 which produce arm tubes or casings 25 with white tapered ends 26, to simulate hands, as shown in Fig. 7. These arm casings are turned right side out and stuffed to a suitable roundness to form an arm 27 and the open ends thereof are closed by seams 28.

The second sock 29 of the pair, complete as shown in Fig. 6, is pulled down over the stuffed body shown in Fig. 5 in such a manner that heel part 30 of the former covers sewed up opening 23 of the latter, the face side of the doll, the toe portion 31 of the former extending rearwardly from the head 95 part of the doll figure. A colored piece of yarn, string or ribbon 32 corresponding to the color of the socks used in making the doll, or suitably contrasting with that color is pulled tightly around the upper end of the 100 doll figure, just below the heel part of outer sock 29 and is tied in a bow knot 33 on the front side of the neck 34 thus formed on the figure. The head and trunk parts 35 and 36, respectively, of the figure, are thus clearly defined.

Arm parts 28 as shown in Fig. 8, are now sewed along seams 27 to outer sock 29, on opposite sides thereof, at suitable points for representing the shoulders of the figure, so 110 that their tapered ends extend at a downwardly inclined angle to the body. Colored

yarn, string or ribbon 37 similar to that forming the neckband 32 are tied tightly in a bow knot around the arms, adjacent their tapered ends to represent wrist-bands and 5 similar bands 38 are similarly tied adjacent the lower ends of the legs to represent ankle bands.

The ribbed part 39 of outer sock 29 is turned upwardly on legs 19 to form a roll 40 at approximately 10 the middle of the figure, which gives that part of the outer sock extending below the head of the figure, the appearance of a jacket or coat. Eyebrows 41 and eyes 42 are embroidered with black thread or 15 yarn and nostrils 43 and mouth 44 are embroidered with red thread or yarn on the heel 30 of outer sock 29, which forms the face of the figure. The foot portion of outer sock 29 is now pulled forwardly over the head of the 20 figure and then turned upwardly to form a fold 45 around the neck and face and its to portion 31 is pulled tightly over the crown 46 of the head with a circular fold 47 which is pulled down on each side of the 25 head, as at 48, and fastened to fold 45 with rosettes 49 formed of yarn or ribbon corresponding in color with neck-band 32, wrist-bands 37 and ankle-bands 39. The appearance 30 of a tightly fitting colored hat with a white crown is thus produced. Tufts of colored thread or yarn, conforming to the general color scheme, are finally fastened to the front and sides of the jacket as at 50 and 51, respectively, to represent rows of buttons and 35 to hold roll 40 in place.

It will be seen that outer sock 29, thus arranged, forms the face, the head cover, and the jacket or coat of the figure, which finally appears as a chubby doll with a coat and hat 40 of the same color and with necktie, wrist bands, ankle bands and other trimmings of a color to correspond or to contrast therewith. The doll, as shown, is adapted for standing 45 but may be modified for a sitting posture, by running a seam 52 across the point of junction of the legs with the body, after the legs have been stuffed and before the body has

been stuffed. A joint 53 is thus formed which permits the legs to be extended forwardly at right angles to the trunk of the figure, so 50 that it may be placed in a sitting position.

Having thus illustrated and described our invention, we claim:

The method of forming a dressed doll out of a pair of socks which comprises cutting 55 off the toe-portion of the first sock; slitting the ribbed-top portion thereof, longitudinally, front and back; sewing the cut edges of said ribbed-top portion to form two closed leg-tubes; stuffing said leg tubes, lower leg 60 and heel parts, of said first sock, with flexible material, so as to form a suitably rounded body; closing the body opening by suitable stitching; cutting said cut-off toe-portion, longitudinally, into two equal parts, 65 tapered at one end; sewing the cut edges of said equal parts to form arm tubes; stuffing said arm tubes with flexible material to a suitable roundness to represent arms; pulling the second sock over the head-end of 70 said stuffed body until the heel portion of the former becomes stretched over the head end of the latter, so as to form a face thereon; folding the ribbed-top portion of said second sock upwardly to form a roll about the 75 legs of the stuffed body to simulate a coat; folding the toe portion of said second sock to form a tight-fitting hat on the head of the stuffed body with a roll rim encircling the face and neck thereof; attaching the arms 80 to opposite sides of said second sock at suitable points to represent shoulders; tying colored material about the body, arms and legs of the resulting figure to mark off the head, hands and feet thereof; fastening tufts of 85 like material to the hat and coat parts of the figure to form side rosettes on the former and to represent buttons on the sides and front of the latter, and embroidering, with colored material, features on the heel part 90 of said second sock which serves as the face of the figure.
